UNITED STATES PATENT OFFICE

RALPH N. ALDRICH, OF SAN FRANCISCO, CALIFORNIA, ASSIGNOR TO STANDARD STATIONS, INC., OF SAN FRANCISCO, CALIFORNIA, A CORPORATION OF DELAWARE

DESIGN FOR A SERVICE STATION

Application filed February 15, 1932. Serial No. 42,874. Term of patent 14 years.

To all whom it may concern:

Be it known that I, RALPH N. ALDRICH, a citizen of the United States of America, residing in the city and county of San Francisco, State of California, have invented a new, original, and ornamental Design for a Service Station, of which the following is a specification, reference being had to the accompanying drawing, forming part thereof.

Figure 1 is a front elevational view of a service station, Figure 2 is a top plan view,

and Figure 3 is an elevational view of the end portion of the design shown in Figure 1 showing my new design. The rear of the building is substantially the same as the front.

I claim:

The ornamental design for a service station, as shown and described.

Signed at San Francisco, California, the 9th day of February, 1932.

RALPH N. ALDRICH.
